United States Patent Office.

WILLIAM BARTLETT, OF LITTLE HOCKING, OHIO.

Letters Patent No. 106,455, dated August 16, 1870.

IMPROVEMENT IN FENCE.

The Schedule referred to in these Letters Patent and making part of the same.

To all whom it may concern:

Be it known that I, WILLIAM BARTLETT, of Little Hocking, in the county of Washington and State of Ohio, have invented a new Improved Fence; and I do hereby declare the following to be a full, clear, and exact description of the same, reference being had to the accompanying drawing, in which—

Figure 1 is a perspective view;

Figure 2 is a side elevation of one section of the fence;

Figure 3 are transverse horizontal sections, showing the manner of connecting the end posts of adjacent sections; and

Figure 4 is a top view.

This invention relates to a zigzag or worm-fence, and consists in posts planted at an inclination, all leaning inward or toward the vertical plane, cutting centrally lengthwise of the fence, for the purpose of rendering the fence firmer than as though the posts were upright.

In the drawing—

a are the posts, planted in zigzag order, two at each angle, and leaning inwardly; or, in other words, the posts, at alternate corners, are inclined toward the

central plane of the fence, whereby a structure pyramidal in its nature is formed, and the fence thereby strengthened.

b are the clamps by which the two posts at each corner are united near their tops.

c are the clamps by which the same posts are united near their lower ends.

d e f are the three boards that form each section of the fence, whereof the upper boards are shortest, the lower boards longest, and the boards *e* intermediate in length, as well as in position, which variation in length is rendered necessary by the opposite outward inclination of the post at each corner of the fence.

Having thus described my invention,

What I claim as new, and desire to secure by Letters Patent, is—

The posts *a*, planted in zigzag order, and inclined at alternate corners of the fence inwardly, or toward the vertical plane, passing centrally lengthwise of the fence, substantially as described.

WILLIAM BARTLETT.
